WORK STATION UNIT FOR PRODUCT ASSEMBLY OR THE LIKE

Douglas M. Sandefur, Los Angeles, Calif., assignor to
Sandefur Engineering Co., Inc., Lawndale, Calif., a
corporation of California

Filed Nov. 2, 1962, Ser. No. 72,351

Term of patent 14 years

(Cl. D55—1)

FIG. 1.

FIG. 4.

FIG. 2.

FIG. 3.

FIG. 5.

FIG. 7.

FIG. 6.

FIG. 1 is a front perspective view of a work station unit for product assembly or the like, showing my new design;

FIG. 2 is a top plan view thereof;

FIG. 3 is an end elevation view thereof;

FIG. 4 is a transverse section thereof taken along plane IV-IV of FIG. 2;

FIG. 5 is a front elevation view of another embodiment of the work station unit shown in FIG. 1 and differing therefrom only in the appearance of the racks;

FIG. 6 is a transverse section thereof taken along plane VI-VI of FIG. 5; and

FIG. 7 is a transverse section thereof taken along plane VII-VII of FIG. 5.

The tray members in FIGS. 4 and 7 are shown broken away for convenience of illustration.

I claim:

The ornamental design for a work station unit for product assembly or the like, as shown and described.
